SLICING MACHINE KNIFE SCRAPER

William H. Fryer, Dayton, Ohio, assignor, by
mesne assignments, to The Hobart Manufacturing
Company, Troy, Ohio, a corporation of
Ohio

Application January 29, 1932, Serial No. 589,583

1 Claim. (Cl. 146—102)

This case relates to a scraper construction for disk knives of food slicing machines.

The object of the invention is to provide a novel scraper device for slicing machines.

5 More particularly, the object is to provide a novel adjustably and resiliently mounted scraper for a slicing machine.

Further and other objects and advantages will be hereinafter set forth in the accompanying 10 specification and claim, and shown in the drawings, which by way of illustration show what is now considered to be the preferred embodiment of the invention.

In the drawings:

15 Fig. 1 is an elevation of the slicing machine from the feeding side,

Fig. 2 is a detail plan view of one form of scraper, partly in section,

Fig. 3 is a side view of this scraper,

20 Fig. 4 is a section on line 4—4 of Fig. 3,

Fig. 5 is a plan view of another form of scraper,

Fig. 6 is a side view thereof, and

Fig. 7 is a top view partly sectioned of still

another form of scraper.

25 Scrapers are used in slicing machines to clean the knife of particles of food adhering thereto during the operation of slicing an article. The operation of these machines in general is as follows:

30 An article to be sliced is supported on the carriage 10 which runs on guide tracks 11 and 12 carried by the frame 13. While the article is being held against the gage plate 14, the carriage 10 is advanced towards the disk knife 15 rotated by any suitable means, the knife cutting a slice from the article during the movement of the carriage. A cover plate 16 over the knife and rear plates and guards 17 and 18 prevent movement of the part of the article which has 35 passed the cutting edge towards the plane of the knife during the slicing operation.

35 As the knife rotates in slicing an article, it picks up and carries around scraps of the article which are scraped from the knife by a scraper blade. In Figs. 1 to 4 is shown one form of scraper construction comprising a scraper blade 20 having a vertical portion 21 and extending therefrom a beveled portion 22 engaged with the knife edge for scraping particles therefrom. A

40 screw 23 passing freely through the vertical portion 21 clamps the blade to a square stud 24 which extends through a square hole in closure plate 25 and into the socket 26 in the enlarged head of the horizontal arm of bracket 27. The 45 lower end of stud 24, as viewed in Fig. 2 is pro-

vided with a plate 28. Between plates 25 and 28 is located a coil spring 29 surrounding stud 24. The spring urges the stud and the blade 20 carried thereby rearwardly away from the knife. A screw 30 threaded into the head 26 abuts the plate 28 to determine the position the scraper takes under influence of spring 29.

5 The vertical arm of bracket 27 is fixed to the frame 13 of the slicer by screws 32.

During the rotation of the disk knife, the 10 scraper just described scrapes the knife rim of all particles of food adhering thereto. Particles which do not fall free of the scraper are forced by the rotation of the knife upwardly along the bevel portion into the space between the vertical 15 portion 21 and the knife surface. The particles received in this space do not therefore force the scraper away from the knife and render it useless as would occur were the entire scraper substantially flush with the surface of the knife, as in 20 former practice.

25 In Figs. 5 and 6 is shown another form of scraper in which the entire scraper blade 35 is beveled similarly to portion 22 of the first described form and the vertical portion omitted. The blade 35 is received between and pinned to the furcations 36 of a round member 37 threaded at its outer end. The blade 35 has a pivotal movement in either direction in its own plane limited by contact of the rear end thereof with 30 the base of the U-shaped slot formed by the furcations 36. The member 37 passes freely through the head 39 of the bracket 40 similar to bracket 27 of the first described form and similarly secured to the slicing machine. The head 35 39 of the bracket has a transverse slot in which is located a knurled thumb nut 41 in threaded cooperation with the stem of member 37. By turning nut 41, the member 37 and the scraper blade carried thereby are adjusted relative to the surface of the knife to properly engage the knife. To lock the member 37 in adjusted position, a nut 42 is threaded onto the outer end of the member 37 and adjusted to abut the outer end face of the head 39. To hold the member 37 against rotation in the bracket, a screw 44 is threaded into the head 39 and extends into a longitudinal slot 45 in the member 37.

50 The disposition of the bevel scraper blade 35 relative to the knife surface is such that particles scraped from the knife surface which do not drop down are forced outwardly along the bevel and as they accumulate do not force the scraper away from the knife surface and out of scraping en-

gagement therewith. The limited pivotal movement of the scraper blade 35 permits it to self align with the knife surface which it engages and which may not be absolutely uniform along its entire circumferential length. Furthermore, by permitting pivotal action of the blade it accommodates itself to the slightly waving motion of the knife surface during rotation thereof.

In Fig. 7 is shown still another form of the invention in which the blade 50 is similar to the blade 20 of the first form but is rigidly riveted to the round hollow stud 51 which extends into the socket 52 of the head 53 of the angular bracket 54. Inside the hollow of stud 51 is a coil spring 55 which at its lower end abuts a plate 56 impinged by the upper end of a screw 57 threaded into the head 53. A screw 58 threaded into the head 53 projects into the longitudinal slot 59 of the stud 51 to prevent rotation thereof. Spring 55 urges the scraper blade towards the knife and permits the blade to yield to the wavy movement of the knife surface during rotation. By turning screw

57, the blade 50 may be adjusted to more or less firmly engage the knife surface.

While there has been shown and described and pointed out the fundamental novel features of the invention as applied to the several modifications it will be understood that various omissions and substitutions and changes in the form and details of the devices illustrated and in their operation may be made by those skilled in the art without departing from the spirit of the invention. I therefore intend to be limited only as indicated by the scope of the following claim:

In a slicing machine including a rotatable disk knife for slicing food; a scraper device comprising a thin blade for engaging the knife to remove particles therefrom, a member carrying the blade, a bracket, and means for yieldably non-rotatably and slidably supporting the member on the bracket for movement transversely to the plane of knife to adjust the frictional engagement between the blade and the knife edge.

WILLIAM H. FRYER.
